UNITED STATES PATENT OFFICE.

WILLIAM H. MATTHIES, OF HACKENSACK, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed November 29, 1926. Serial No. 151,291.

This invention relates to telephone systems in which connections are established by means of automatic switching apparatus under the control of an impulse transmitter and has for its object the provision of an improved sender for recording impulses from such a transmitter.

According to one aspect of the present invention the sender has a primary register and a plurality of secondary registers with means for simultaneously setting said primary register and one of said secondary registers, and so arranged that the primary register is released at each setting thereof, while the secondary registers are successively operated and locked.

In larger telephone systems the automatic switches employed in establishing connections are generally controlled by means of a central office sender. An impulse transmitter or dial at the subscriber's substation is operated in accordance with the number of a called subscriber and a record of this number is established on the control device. The record is usually made on a plurality of registers one for each digit of the called number which registers are successively rendered effective by means of a master switch or by the use of a primary register which is positioned by the impulses and subsequently positioned by the other registers. Where the digits comprising the wanted number are low, such as 1 or 2, the digits may follow one another so quickly as to allow scant time for the transfer from one register to another, thus necessitating exceptionally quick operating apparatus. The system of the present invention, however, provides for the simultaneous operation of the primary register and the secondary register with means to hold each secondary register as soon as the registration is completed. These secondary registers thereupon operate switch controlling registers by means of which the connection to the called subscriber's line is established.

Reference is made to Patent No. 1,623,777, granted April 5, 1927, to W. W. Carpenter, and to an application of F. A. Stearn, Serial No. 152,594, filed Dec. 4, 1926, for systems in which a register arrangement of the sort disclosed has been employed.

A clearer understanding of the invention will be obtained from a consideration of the following description in connection with the appended claims and attached drawings in

which Fig. 1 shows a diagrammatic train of switches and means for associating a district selector with a sender embodying the present invention. Fig. 2 shows the primary register and two

of the secondary registers. Figs. 3 and 4 show additional secondary registers. Assuming that the subscriber at substation 100 wishes to talk to the subscriber at substation 101, he will remove his receiver from the switchhook to cause line finder 102 to associate his line with a district selector which is locked.

Fig. 1 shows a diagrammatic train of switches and means for associating a district selector with the sender. This may be brought about in any desired manner, a link circuit of the type disclosed in U. S. Patent No. 1,567,072, granted to W. H. Matthies, on December 29, 1925, having been indicated diagrammatically for purposes of illustration. As soon as the link circuit has functioned to associate the sender with the district selector a circuit is closed from ground through the winding of relay 107, through the link circuit to battery in the district selector. The operation of relay 107 closes the circuit for sequence switch magnet 108 which controls the operation of the sender advancing the sequence switch to position 2. As soon as sequence switch 108 reaches position 2 an off-normal ground is supplied to conductor 109 operating relay 110 to remove battery from the terminal corresponding to this sender in the bank of the sender selector of the link circuit for the purpose of rendering the sender non-selectable to other links. A circuit is also completed with ground on conductor 109 over the back contact of relay 226 to the winding of relay 227 and battery. Relay 227 operates and extends conductors 251, 252, 253, 254, 255 to the relays of register 220 preparing for the reception of the first digit. It also prepares the tone circuit.

At the same time a circuit is completed which may be traced from battery through the right winding of relay 103, through the link circuit, lower contacts of cam 104, through the line finder 102, dial 105 and the substation circuit, back to line finder 102, upper contacts of cam 106 through the link circuit, to ground through resistance 124. Relay 103 operates in this circuit and closes

an obvious circuit for relay 111. Relay 111 in turn closes a circuit for relay 112 and relay 112 closes a circuit for relay 113. As soon as relay 113 operates a circuit is closed 5 from ground through the secondary winding of tone coil 114, left winding of relay 103, upper front contact of relay 227, inner front contact of relay 113 to ground. The tone in the primary winding of coil 114 is induced 10 in the circuit just traced and from thence into the right winding of relay 103 and the receiver of the called subscriber. This tone is an indication to the calling subscriber that a 15 sender has been associated with his line and is ready to receive the called number.

Assuming that the called subscriber's number is DILLon 6780 the subscriber will operate his dial to send out three series of impulses of 3, 4 and 5 each, corresponding to 20 the office code, and 6, 7, 8 and 10 each, corresponding to the numerical designation. As the dial returns to normal following the first digit it will open the circuit of relay 103 three 25 times. Relay 103 releases at each interruption and opens the circuit of relay 111 which also releases. The release of relay 111 opens the circuit of relay 112 but that relay, being slow to release, remains operated between pulses. With relay 111 released a circuit is 30 closed from battery through the winding of relay 115, outer back contact of relay 111, outer front contact of relay 113 to ground, relay 113 being held operated by its slow-release character, as well as the slow-release character of relay 112. Relay 115 is also slow to 35 release so that it does not retract its armature during the short operated periods of relay 103 during dialing but does close its back contact between digits.

At the first release of relay 103 a circuit is closed from ground over the back contact of relay 103, outer front contact of relay 112 to conductor 116 and thence over the upper back contacts of relays 210, 208, 206, 204 and 40 202 to the winding of relay 201 and battery. Relay 201 operates and closes a locking circuit for itself through the winding of relay 202, front contact of relay 201, upper back contact of relay 204, conductor 250 to ground 45 over the middle back contact of relay 111 and the outer front contact of relay 113, or over the front contact of relay 115 and the inner front contact of relay 113. This alternative arrangement insures the closure of the locking circuit for the relays, the circuit over relay 111 being ready before relay 115 has time to operate, and the circuit over the front contact of relay 115 remaining closed throughout each digit. Relay 202 does not 50 operate in the above traced locking circuit until the reoperation of relay 103, following the first pulse, opens the energizing circuit of relay 201 and removes the shunt around the winding of relay 202. As soon as relay 202 55 operates a circuit is closed from ground over

its lower front contact, conductor 252, middle lower front contact of relay 227, upper winding of relay 222 to battery. The next interruption of the circuit of relay 103 by the dial connects ground to conductor 116, 70 over the back contacts of relays 210, 208, 206 and 204, front contact of relay 202 to the winding of relay 203 and battery. As in the case of relay 201, relay 203 closes a locking circuit through the winding of relay 204 75 extending over the front contact of relay 203 and the back contact of relay 208 to grounded conductor 250. At the close of the pulse relay 204 operates opening the locking circuit of relays 201 and 202 thus in turn opening the 80 circuit of relay 222. It also connects ground over its lower front contact to conductor 253 completing a circuit over the inner lower front contact of relay 227, upper winding of relay 223 to battery. At the next impulse 85 the release of relay 103 completes a circuit from ground over its back contact as before traced to conductor 116, back contacts of relays 210, 208 and 206, front contact of relay 204, winding of relay 205 to battery. Relay 90 205 closes the usual locking circuit for itself through the winding of relay 206 to grounded conductor 250 over the back contact of relay 208. At the end of the pulse, relay 206 operates, but since the locking circuit of relays 95 203 and 204 extends over the back contact of relay 208, these relays also remain operated and ground remains connected to conductor 253 and is connected to conductor 252. In consequence, relays 222 and 223 are both operated 100 at this time.

Since there are only three impulses in this series relay 103 now remains operated for a sufficient length of time to permit relay 115 to release. The release of relay 115 completes 105 a circuit from ground over the inner front contact of relay 113, back contact of relay 115, conductor 117, over a chain circuit including the back contacts of relays 437, 427, 417, 337, 327, 317 and 237, lower winding of relay 226, lower front contact and winding of relay 223 to battery and also over the lower front contacts of relay 223, lower front contact and winding of relay 222 to battery. Relay 226 operates and closes a 110 locking circuit for itself from battery through its upper winding and lower front contact to grounded conductor 109. The operation of relay 226 also closes a direct locking ground for relays 222 and 223 independent 115 of the chain circuit through the other registers. A circuit is also closed from battery through the winding of relay 237, back contact of relay 236, lower front contact of relay 226 to grounded conductor 109, operating relay 237 to extend conductors 251 to 120 255 to release after register 230.

It will be noted that the holding circuit for relay 222 extends through the front contact of relay 223 and also over the front contact of 125

relay 225. This is due to the fact that the digit 1 is never employed as the first digit of an office code since it may be simulated by accident. Therefore the relay 222 is not held operated except in combination with other relays.

During the interval between digits relay 111 remains operated. Therefore the release of relay 115 disconnects ground from conductor 250 releasing the operated counting relays of primary register 200. It will be noted that the contacts of relay 115 are so arranged that ground is not disconnected from conductor 250 until after the circuit of relay 226 is completed so that the relays of register 200 are not released until after the relays of register 220 are locked up.

When the subscriber operates his dial to send the second digit 4, he will open the circuit of relay 103 four times. Relays 201 to 203 will be operated in the manner described for the first digit in response to the first three pulses. Relays 232 and 233 will be operated alone and in combination as described for relays 222 and 223. In response to the fourth impulse relay 207 is operated and closes a locking circuit for itself through the winding of relay 208 over the back contact of relay 210 to conductor 250. When relay 208 operates at the completion of the pulse, relays 203, 204, 205 and 206 are all released removing ground from conductors 252 and 253. Relay 208 connects ground to conductor 254 to operate relay 234. The release of relay 115 at the end of the digit causes the operation of relay 236 in a circuit similar to that for relay 226 except that the back contact of relay 237 is not included. Relay 236 in operating closes ground from conductor 109 over its lower front contacts, and lower front contact and lower winding of relay 234 to battery holding that relay operated. The operation of relay 236 completes a circuit for relay 317 after which the relays of register 200 are released, and the circuit prepared for receiving the third digit.

The first four impulses of the third digit, 5, are received as previously described. The fifth interruption of the circuit completes a circuit for relay 209, which in turn closes a locking circuit for itself through the winding of relay 210, over the back contact of relay 204 to conductor 250. Relay 210 opens the locking circuit of relays 207 and 208 and connects ground over its lower front contact, lower front contact of relay 212 to conductor 255, middle upper front contact of relay 317 to the upper winding of relay 315 and battery. Relay 210 in operating also closes a circuit from battery to the winding of relay 211, back contact of relay 212, upper front contact of relay 210 to grounded conductor 250. Relay 211 closes a locking circuit for itself through the winding of relay 212 which is ineffective as long as relay 210 re-

mains operated. Following the last digit relay 115 is released as above described, relay 316 is operated in the same manner as relay 226, holding relay 315 operated and extending a circuit for operating relay 327.

At the completion of this digit a circuit is closed from ground on conductor 109, front contact of relay 316, conductors 301 and 256, winding of relay 119 to battery. Relay 119 connects ground to conductor 120 to initiate the operation of the decoder connector which serves to connect an idle decoder with the code registers 220, 230 and 310 to translate or decode that registration and to transfer the decoded registration to the selection registers which control the operation of the district selector 150 and an office selector if necessary, by means of the usual fundamental circuit and reverteive impulses to select a trunk outgoing to the wanted office.

When the subscriber dials the fourth digit 6 the relays of register 200 are operated in the same manner as was described for the first five impulses. The 6th impulse will cause the completion of a circuit from ground to conductor 116 over the front contact of relay 210 and the back contact of relays 208, 206, 204 and 202 to the winding of relay 201 which operates in the same manner as before. The locking circuit of relays 209 and 210 is maintained at this time so that upon the operation of relay 202 at the close of the last impulse ground is connected to conductors 252 and 255 causing the operation of relays 325 and 322 in register 320. As before the release of relay 115 causes the operation of relay 326, the release of register 200 and the operation of relay 337 to render register 330 effective to receive the next digit.

When a subscriber dials the next digit, 7, the register 200 operates in the manner described for the first 6 impulses. The 7th impulse causes the completion of the circuit of relay 208 over the front contact of relay 210, back contacts of relays 208, 206, 204 and front contact of relay 202. The locking circuit of relay 203 is the same as on its first operation. At the end of the pulse, relay 204 operates opening the locking circuit of relays 201, 202, 209 and 210. It also connects ground to conductor 253. The release of relay 210 permits relay 212 to operate in the locking circuit of relay 211 and the operation of relay 212 connects ground over the back contact of relay 210 and the inner front contact of relay 212 to conductor 255 so that relays 333 and 335 are operated at the end of the last impulse. As before, the release of relay 115 causes the operation of relay 336, the release of register 200 and the operation of relay 417.

In response to the dialing of the next digit, 8, the register 200 is operated as described for the first seven impulses and the circuit for operating relay 205 in response to the 8th

digit is the same as first traced. The locking circuit is also the same as previously described. The locking circuit of relays 211 and 212 is independent of any of the other 5 relays and therefore these relays remain operated until the register is released. It will be remembered that the operation of relay 206 does not release relays 203 and 204. Therefore at this time conductors 252, 253 and 255 10 are grounded, causing the operation of relays 412, 413 and 415. The release of relay 115 following the last impulse causes the operation of relay 416 holding relays 412, 413 and 415 operated, releasing register 200 and 15 operating relay 427.

In response to the last digit 0 the register 200 records the first 8 impulses in the manner described. The 9th digit is recorded on relays 207 and 208 and the tenth digit causes 20 the operation of relays 209 and 210. With relays 209, 210, 211 and 212 operated, a circuit is closed from ground over the front contact of relay 210, lower front contact of relay 212 to conductor 251 and thence over the lowermost front contact of relay 427 to the winding of relay 421, the operation of relay 210 disconnecting ground from conductor 255 and releasing relay 425 which has been operated since the reception of the fifth impulse. 30 The release of relay 115 causes the operation of relay 426, release of register 200 and the operation of relay 437. Since no stations designation is included, register 430 will not be positioned.

35 The selection of an outgoing trunk to the wanted office is controlled by sequence switch 108. Following the completion of these selections the selection register is released and the sequence switch is advanced to a position 40 in which the thousand register 320 is effective to control the setting of one of the selection registers. For a detailed description of these operations reference is made to the application of F. A. Stearn referred to 45 above.

What is claimed is:

1. In a registering system, a primary register, a plurality of secondary registers and means to simultaneously position said primary register and set one of said secondary registers in its permanent registering position.

55 2. In a registering system, a primary register, a plurality of secondary registers, means to transmit series of impulses to said registers, means to simultaneously and successively position said primary register and one of said secondary registers in accordance with the numerical position of each impulse of a 60 series, and means to hold said secondary register in a position corresponding to the last impulse received.

65 3. In combination, a primary register, a plurality of secondary registers, means to simultaneously position said primary regis-

ter and one of said secondary registers, and means to simultaneously hold the positioned secondary register in said position and to associate the primary register with the next secondary register.

4. In a registering system, means progressively positioned in response to a series of impulses, a plurality of registers, means to position one of said registers simultaneously with the positioning of said responsive means, and means operable upon the completion of a series of impulses to simultaneously hold the positioned register and to associate said responsive means with the next register.

5. In combination, a primary register, a plurality of secondary registers each comprising a plurality of relays arranged to be operated in combinations constituting a code, means to simultaneously and successively position said primary register and one of said secondary registers in accordance with the numerical position of each impulse of a series of impulses and means to hold said secondary register in the position corresponding to the last impulse received.

6. In a registering system, means progressively positioned in response to a series of impulses, a plurality of registers, means to successively position one of said registers simultaneously with the positioning of said responsive means in accordance with the numerical position of each successive impulse in a series, and means operable upon the completion of said series of impulses to simultaneously hold the register in the position corresponding to the last impulse received and to associate said responsive means with the next register.

7. In a registering system, means progressively positioned in response to a series of impulses, a plurality of registers each comprising a plurality of relays arranged to be operated in combinations according to a code, means to successively position one of said registers simultaneously with the positioning of said responsive means in accordance with the digit represented by each successive impulse, and means operable upon the completion of said series of impulses to simultaneously hold the register in the position corresponding to the last impulse received and to associate said responsive means with the next register.

8. In a registering system, a primary register, a plurality of secondary registers, and means to position the secondary registers by simultaneously operating the primary register with each of said secondary registers in succession.

9. In a registering system, a primary register, a plurality of secondary registers, means to position the secondary registers by simultaneously operating the primary register with each of said secondary registers in succession, and means to release the primary

register and lock the secondary register upon the completion of each operation.

10. In a registering system, a primary register, a plurality of secondary registers, means to position the secondary registers by simultaneously operating the primary register with each of said secondary registers in succession, and means operable upon the completion of each simultaneous operation to prepare the primary register for a subsequent operation and lock the secondary registers positioned by said operation.
11. In a registering system, a progressively operable primary register, a plurality of secondary registers, each progressively responsive with each operation of said primary register when associated therewith, and means for successively associating said primary register with each secondary register.

12. In a registering system, a progressively operable primary register, a plurality of secondary registers, each progressively responsive with each operation of said primary register when associated therewith, means for successively associating said primary register with each secondary register, and means for locking each secondary register in the position taken by its last operation.

13. In a registering system, series of impulses to be registered, a primary register, a plurality of secondary registers for recording the settings of said primary register, means to successively associate said primary register with said secondary registers, and means in said primary register and the associated secondary registers to simultaneously register each impulse of a series.

14. In a registering system, series of impulses to be registered, a primary register, a plurality of secondary registers for recording the settings of said primary register, means to successively associate said primary register with said secondary registers, means in said primary register and the associated secondary registers to simultaneously register each impulse of a series, and means to lock said secondary registers to record any of said registrations.

15. In a registering system, series of impulses to be registered, a primary register, a plurality of secondary registers for recording the settings of said primary register, means to successively associate said primary register with said secondary registers, means in said primary register and the associated secondary registers to simultaneously register each impulse of a series, and means to lock said secondary registers to record any of said registrations and prepare said primary register for registering a subsequent series of impulses.

16. In a registering system, a primary register comprising a plurality of relays operable in continuous progression, a plurality of secondary registers each comprising a plu-

rality of relays operable in combinations, and means to simultaneously operate progressively a series of relays in said primary and secondary registers for controlling a setting of a combination of said secondary register relays.

17. In a registering system, a primary register comprising a plurality of relays operable in continuous progression, a plurality of secondary registers each comprising a plurality of relays operable in combinations, means to simultaneously operate progressively a series of relays in said primary and secondary registers for controlling a setting of a combination of said secondary register relays, and means to associate said primary register with each secondary register for controlling the settings of said secondary registers according to successive operations of said primary register.

18. In a registering system, a primary register comprising a plurality of relays operable in continuous progression, a plurality of secondary registers each comprising a plurality of relays operable in combinations, means for associating said primary register with a secondary register, means to progressively operate a plurality of relays in said primary register, means for causing said secondary register to take different settings simultaneously with the operation of successive primary register relays, and means to lock said secondary register in the setting last taken.

19. In a registering system, a series of impulses to be registered, a primary register comprising a plurality of relays less in number than the maximum number of impulses to be registered, a plurality of secondary registers for recording the settings of said primary register, means to successively associate said primary register with said secondary registers, and means in said primary register and associated secondary registers to simultaneously register each impulse of a series.

20. In a registering system, a series of impulses to be registered, a temporary register comprising a plurality of relays less in number than the maximum number of impulses to be registered, a plurality of permanent registers for recording the settings of said temporary register, means to successively associate said temporary register with said permanent registers, means in said temporary register and associated permanent registers to simultaneously register each impulse of a series, and means to lock said permanent register to record any of said registrations.

21. In a registering system, a series of impulses to be registered, a temporary register comprising a plurality of relays less in number than the maximum number of impulses to be registered, a plurality of permanent registers for recording the settings of said

temporary register, means to successively associate said temporary register with said permanent registers, means in said temporary register and associated permanent registers to simultaneously register each impuse of a series, and means operable upon the completion of a series of impulses to prepare said

temporary register for registering a subsequent series of impulses and lock the associated permanent register in position. 10

In witness whereof, I hereunto subscribe my name this 26th day of November, A. D. 1926.

WILLIAM H. MATTHIES.
